UNITED STATES PATENT OFFICE.

WALTER T. GORTON, OF THE UNITED STATES ARMY, SPRINGFIELD, MASSACHUSETTS.

SEAR MECHANISM.

Application filed July 11, 1924. Serial No. 725,441.

(GRANTED UNDER THE PROVISIONS OF THE ACT OF MARCH 3, 1883, 22 STAT. L., 625.)

The invention described herein may be manufactured and used by or for the Government for governmental purposes without the payment to me of any royalty thereon.

5 My invention relates, in general terms, to a sear mechanism designed to maintain the firing pin of a gun retracted when in cocked position. More particularly my invention resides in the provision of a single element 10 within the bolt which will effectively retract the firing pin and prevent its release until the breech mechanism is locked in forward position and which is so disposed with respect to a trip element that release of the 15 firing pin will only be accomplished by a relatively long movement of the trigger effected by a correspondingly small effort.

The principal objects of my invention are: to provide a sear mechanism embodying a 20 single element which will automatically perform the function usually obtained by the cocking lever, sear and sear slide with their actuating springs and holding bolts; to so construct the sear that a relatively small 25 thrust will initiate its withdrawal to inoperative position; to complete the withdrawal operation through the instrumentality of the firing pin; to provide means for positively insuring retraction of the firing pin upon 30 recoil of the bolt and to absolutely prevent the release of the firing pin except when the breech mechanism is fully forward and locked.

To these and other ends, my invention consists in the construction, arrangement, and combination of elements described herein-after and pointed out in the claims forming a part of this specification.

One embodiment of my invention is illustrated in the accompanying drawings, in which,

Fig. 1 is a top plan view of a gun broken to show the arrangement of trip and sear;

Fig. 2 is a horizontal section of the bolt 45 showing the sear and firing pin in cocked position;

Fig. 3 is a horizontal section of the bolt showing the sear and firing pin in firing position;

50 Fig. 4 is a sectional view taken on the line 4-4 of Fig. 3;

Fig. 5 is a detailed view of the sear in rear elevation;

Fig. 6 is a plan view of the sear;

Fig. 7 is a detailed view in side elevation 55 of the firing pin; and

Fig. 8 is a fragmentary plan view of the firing pin.

In the accompanying drawings in which like characters of reference designate like or 60 similar parts,

5 and 6 indicate the side plates of the receiver of a gun to which is attached in any suitable manner a spade grip 7. A forked trigger 8 pivotally mounted on the spade 65 grip 7 carries opposite lugs 9 on its upper portion in rear of the side plates 5 and 6, which lugs are adapted for engagement with a trip element operable by the trigger.

The trip element may conveniently be an 70 elongated T bar 10, formed at its rear end with a laterally projecting lug 11 adapted for engagement with a lug 9 of the trigger. The cross arm of the T bar formed at its 75 forward end, provides an outwardly projecting arm 12, and an inwardly projecting arm 13, which latter arm projects through a slot 14 formed in the side plate 6 and is formed with a beveled end for engagement with the sear, as will be presently described. 80

The T bar is preferably mounted in a housing 15, which may be connected to the side plate in any suitable manner; a convenient connection, as herein shown, consisting in providing a beveled lug 16 on the casting 85 adapted to enter a slot 17 in the side plate 5 and engage the beveled rear wall of the slot. A bolt 18, formed with a tapered head, connects the front end of the housing 90 to the side plate, the tapered head engaging the curved beveled front wall of the slot 14 and being drawn tightly thereagainst by a nut 19.

The housing is formed with an offset portion 20 to receive the outwardly projecting 95 arm 12 and to house a spring 21, the forward end of which seats against the arm 12 and the rear end against the rear wall of the offset. The spring acts to normally retain the trip bar in its forward, idle position. 100

The side plate 5 has a gradually extending portion 22 which is abruptly terminated as at 23 and is adapted to form a cam surface 24 for a purpose which will appear hereinafter. If desired, this construction 105 may be modified and a cam for performing a similar function may be attached to the side plate.

A bolt 25 adapted for slideable movement with respect to the side plates 5 and 6 is formed with a base portion 26 and a reduced extension 27. The forward portion of one side of the base 26 is cut away as at 28 to accommodate the laterally projecting lug 11 of the trip 10 when the bolt is moved rearwardly. Positioned centrally within the bolt 25 is a longitudinal bore in which is reciprocally mounted a firing pin 29, having its forward portion hollowed to enclose a coil spring 30, which is seated against a pin 31 rigidly mounted in the bolt and passing through a slot 32 in the firing pin 29. The base of the firing pin 29 is formed with a squared bottom 33, the forward face of which is beveled as at 34 at an angle of 45° to form a cam surface.

The base 26 of the bolt 25 is bored transversely from side to side to embrace a sear 35 adapted for slideable movement within the bolt. One end of the sear is beveled as at 36 to co-act with the cam surface 24 of the side plate 5, so that when the bolt moves rearwardly, the sear 35 will be forced completely within the bolt 25 where it is maintained in fixed position by the straight sides of the plate 6. The opposite end of the sear 35 is reduced as at 37 on a plane parallel to the longitudinal axis of the bolt to form a straight sided lug 38 of the same width as the lateral lug 11 of the trip 10 and having a forwardly extending beveled face 39 for contact with the beveled end of the arm 13.

The upper central portion of the sear 35 is cut away as at 40, forming square walls 41 and 42, to a sufficient depth to provide clearance for the cylindrical portion of the firing pin 29 when the bolt and firing pin have been moved to the rear and when the sear is completely encased by the bolt. Adjacent the left wall 42 the sear is cut away to a greater depth to form a bevel surface 43 intermediate the walls 41 and 42 and which is adapted to cooperate with the beveled face 34 formed on the forward portion of the base 33 of the firing pin. The rear edge of the beveled cam surface 43 is terminated at a point which extends a slight distance beyond the longitudinal bore of the bolt when the sear is normally in locked position so that when the sear 35 is actuated by the trip 10, it will only be necessary for it to be moved a short distance when the cam 34 of the firing pin after being cammed out of a curved recess 44 spaced a slight distance from the terminus of the cam 43 is afforded a point of entry against the cam 43 of the sear and under the action of the firing pin spring 30 completes the withdrawal of the sear to inoperative position. If desired, the cams 34 and 43 may be formed with slightly inclined or corresponding concave and convex surfaces to reduce vibration of the movable elements.

In operation, when the trigger is actuated, the lug 9 formed thereon acts on the lug 11 of the trip 10 to retract the same against the tension of the spring 21. The arm 13 on the trip bearing on the cam surface of the lug 39 of the sear cams the firing pin out of the recess 44 and moves the sear to the right a sufficient distance to permit entry of the cam 34 of the firing pin, which under the force of the firing pin spring is now free to move forward thereby forcing the sear to continue its withdrawal movement until it comes to rest against the side plate 5. When the force of the explosion moves the recoiling portions to the rear, the sear 35 riding against the cam 23 of the side plate 5 is forced into the bolt and automatically retracts the firing pin against the tension of the firing pin spring until the cam 34 engages the recess 44 and securely locks the firing pin in cocked position. The firing pin can not be released to the firing position except when the bolt is completely forward and locked as only then the sear will be free to move the required distance to enable the firing pin to be finally released.

If the trigger is held back, as for sustained fire, the forward movement of the bolt after the first shot is fired affords the same relative movement between the sear and the trip, so that the gun will continue to fire automatically within the limits of ammunition until the trigger is released when the trip spring moves both the trigger and the trip to the forward or inoperative position.

I claim:

1. A sear mechanism for fire arms embodying an elongated member having beveled ends, the upper central portion being unequally recessed to provide a cam surface at the juncture of the inequalities.

2. A sear mechanism for fire arms embodying an elongated member having beveled ends, the upper central portion being recessed to provide clearance for a firing pin when the same is being moved to cocked position, and the rear portion being recessed to receive a complementary portion of the firing pin whereby to lock it in cocked position.

3. In a gun, the combination with a bolt and a firing pin, of a sear transversely mounted in the bolt and engageable with the firing pin, and means for moving the sear, said sear being adapted to clear the firing pin when the same is retracted and including means integrally formed thereon to operatively engage the firing pin whereby to retract the same when the bolt is moved to the rear.

4. In a gun, the combination with a bolt and a firing pin, of a sear transversely mounted in the bolt and engageable with the firing pin, said sear being adapted to be manually moved a relatively short dis-

tance and automatically moved a relatively long distance.

5. In a gun, the combination with a bolt and a firing pin, of a sear transversely mounted in the bolt and engageable with the firing pin, said sear being formed with means for operatively engaging the firing pin.

6. In a gun, the combination with a bolt and a firing pin, of a sear transversely mounted in the bolt and engageable with the firing pin, said sear being formed with beveled opposite ends.

7. In a gun a bolt, a firing pin carried by the bolt, a sear engageable with the firing pin and adapted to ride under the firing pin, and means for automatically forcing the sear into engagement with the firing pin to retract the same to inoperative position.

8. In a gun a bolt, a firing pin carried by the bolt and a sear engageable with the firing pin and providing clearance for the firing pin when moving the firing pin to inoperative position.

9. In a gun, the combination with a bolt and a sear, of a firing pin, a spring carried by the firing pin, and means formed on the base of the firing pin and for engaging the sear to force the same laterally with respect to the firing pin when the firing pin is released.

10. In a gun, the combination with a bolt and a firing pin, of a sear transversely mounted in the bolt and engageable with the firing pin, and means for camming the sear into engagement with the firing pin when the bolt is retracted.

11. In a gun, the combination with a bolt and a firing pin, of a sear transversely mounted in the bolt and means for automatici-

cally moving the sear to retract the firing pin and lock it in inoperative position.

12. In a gun, the combination with a bolt and a firing pin, of a sear mounted in the bolt, manually operated means for initiating the withdrawal of the sear, and automatically operated means for completing the withdrawal.

13. In a gun, the combination with a bolt, and a firing pin, of a sear mounted in the bolt and capable of movement to inoperative position only when the bolt is fully forward.

14. In a gun, the combination with a bolt and a firing pin, of a sear transversely mounted in the bolt, and means for positively moving it into locking position.

15. In a gun, a bolt, a firing pin carried by the bolt and a sear moved by reciprocation of the bolt to lock the pin in cocked position.

16. In a gun, a bolt, a firing pin carried by the bolt and a sear reciprocable in the bolt moved by reciprocation of the bolt to lock the firing pin in cocked position.

17. The combination with a firing pin, of a combined sear and pin cocking element movable at right angles to the pin.

18. A firing pin and a sear therefor, the sear operable to cock the firing pin, and the firing pin operating to release the sear after initial movement of the sear toward released position.

19. A bolt, a longitudinally reciprocal firing pin, and a transversely movable sear, said pin and sear arranged for mutual actuation of each other.

20. In a machine gun, a combined firing pin cocking member and sear.

WALTER T. GORTON.
